US00D812673S

(12) **United States Design Patent** (10) Patent No.: **US D812,673 S**
Andersson et al. (45) Date of Patent: **** Mar. 13, 2018**

(54) **MONITORING CAMERA**

(71) Applicant: **AXIS AB**, Lund (SE)

(72) Inventors: **Mathias Andersson**, Hoganas (SE);
Ola Andersson, Helsingborg (SE);
Morten Bergstrom, Bjarred (SE); **Lina Carlsson**, Rydeback (SE); **Johan Hagg**, Lund (SE); **Rafael Portela**, Malmo (SE)

(73) Assignee: **AXIS AB**, Lund (SE)

(**) Term: **15 Years**

(21) Appl. No.: **29/551,403**

(22) Filed: **Jan. 13, 2016**

Related U.S. Application Data

(62) Division of application No. 29/471,651, filed on Nov. 4, 2013, now Pat. No. Des. 750,682.

(57) **CLAIM**

The ornamental design for a monitoring camera, as shown and described.

DESCRIPTION

FIG. 1 is a bottom, front, right perspective view of a monitoring camera in accordance with our design; FIG. 2 is a front elevational view thereof; FIG. 3 is a left side elevational view thereof; FIG. 4 is a right side elevational view thereof; FIG. 5 is a top plan view thereof; FIG. 6 is a bottom plan view thereof; and, FIG. 7 is a rear elevational view thereof.

The broken lines depict portions of a monitoring camera in which the designed is embodied and form no part of the claimed design.

The dot-dash lines denote the boundary of the claim and form no part of the claimed design.

1 Claim, 7 Drawing Sheets
